United States Patent Office

Des. 182,213
Patented Feb. 25, 1958

182,213

STOOL

Harold C. Wiederhold, Oak Park, Ill., assignor to Empire Works, Inc., Chicago, Ill., a corporation of Illinois

Application June 20, 1957, Serial No. 46,668

Term of patent 7 years

(Cl. D15—8)

I claim:

The ornamental design for a stool, substantially as shown.
